UNITED STATES PATENT OFFICE.

JOHN W. SMITH, OF PORTLAND, OREGON.

STORE STOOL AND FOOT-REST.

SPECIFICATION forming part of Letters Patent No. 634,373, dated October 3, 1899.

Application filed November 21, 1898. Serial No. 697,028. (No model.)

To all whom it may concern:

Be it known that I, JOHN W. SMITH, residing at Portland, in the county of Multnomah and State of Oregon, have invented a new and Improved Store Stool and Foot-Rest, of which the following is a specification.

This invention is in the nature of a combined stool and foot-rest more particularly adapted for use in shoe-stores; and it primarily has for its object to provide an appliance of this character of a very simple and economical construction and which will conveniently serve as a means for aiding the salesmen in fitting shoes, particularly on children and stout persons.

My invention comprises certain details of construction and novel combination of parts, including a peculiar form of lock device for holding the swinging rest to its adjusted position, all of which will be first described in detail and then be specifically pointed out in the appended claims, reference being had to the accompanying drawings, in which—

Figure 1 is a perspective view of my improvement. Fig. 2 is a side elevation of the same, the foot-rest being shown in an elevated position in dotted lines. Fig. 3 is a detail view of the foot-rest-frame locking devices.

In its practical construction my invention comprises a pedestal 1 of suitable ornamental shape and of proper height, its top supporting a seat-block 2, while its lower end is tenoned or otherwise made secure to the base 3 of proper supporting area. The base 3 has one end extended, as at 3^a, and such end is bifurcated to receive the lower end of a quadrant-shaped combined guide and lock rack-bar 4, the upper end of which is made fast to the upper end of the pedestal, and such bar has a series of lock-notches 4^a.

5 indicates the foot-rest block, which has the usual heel offset 5^a at the lower outer edge and a spring-heel depression 5^b, as clearly shown in Fig. 1. This rest-block is mounted on a swinging frame comprising a pair of straight rods 6, pivotally secured at their inner ends on the pedestal projected outward to straddle a rack or guide bar 4 and pivotally secured at 6^a to the lower edges 5^a on the foot-block, such frame also including a pair of upper rods 7, pivotally secured

at one end to the pedestal and at the other to the upper (inner) end of the foot-block, such bars being curved so as to admit their being swung without engaging the seat-block.

It will be noticed by reference to Fig. 2 that the distance between the pivotal points of the swinging-frame arms 6 and 7 on the pedestal is considerably greater than the distance between their pivotal point on the foot-rest block 5. The object in thus pivotally connecting the swinging-frame members is an important one, for the reason that as the arms 6 and 7 are swung upward the relative position of the foot-block will constantly but gradually change with the increase of the height thereof from that of nearly horizontal when at its lowermost position to a nearly vertical position when elevated, thereby providing for bringing the foot in a natural position without moving the ankle, thereby enabling the salesman to the more conveniently and properly fit the customer, it also affording a very convenient support for such customer and a benefit to the salesmen.

To prevent undue lateral or side play, the arms 6 and 7 are bent inward where they straddle the bar 4 to travel in close relation thereto and also to admit of the employment of a very simple but efficient detent device for holding the rest-block frame to its adjusted position.

The detent, which is best shown in Fig. 3, comprises a short rock-shaft 8, journaled in the arms 6 and 7, transversely over the bar 4, and provided with a loop or crank portion 8^a, which can be readily moved into or out of engagement with any one of the notches in the bar 4, and for such purpose one end of the shaft terminates in a crank-handle 8^b, with which connects one end of a retractile spring 9, the other end of which is made fast to one of the arms 6, such spring serving to normally hold the detent in a locked engagement with the notched bar 4.

From the foregoing description, taken in connection with the drawings, it is thought that the operation and advantages of my invention will be readily understood. It will be observed that the salesman can quickly pull the shoe-rest frame upward, as the detent will automatically engage with the notches on the bar 4. To depress the said frame, it is only

necessary to manipulate the crank-handle of the detent to release it from the bar 4.

My invention is of an exceedingly simple character; but by reason of the automatic adjusting of the foot-rest block 5 to change its position so as to maintain the foot in its natural condition the same will prove a desirable adjunct to a retail shoe-store.

Having thus described my invention, what I claim, and desire to secure by Letters Patent, is—

1. The combination with the stool-pedestal and the segmental rack-bar, of a swinging frame, comprising a lower member and an upper member, said members having independent pivotal connections with the pedestal; a foot-rest pivotally connected to the outer ends of the said upper and lower swinging-frame members, the pivotal points of such outer ends being closer engaged than the pivotal points of their inner ends, and detents for locking the frame on the rack-bar in a vertical adjusting position, substantially as shown and described.

2. The combination with the stool-pedestal, and a vertically-disposed rack-bar secured thereto; of a swinging frame consisting of a pair of lower arms and a pair of upper arms independently pivotally joined to the pedestal

and held to straddle the rack-bar; and a foot-rest pivotally joined to the outer ends of the said upper and lower straddle members, the pivotal points of connection of the foot-rest being of less separation than the pivotal points of connection of the inner ends of the said straddle-bars, and a detent for locking one set of such straddle-bars in its vertical adjustments on the rack-bar, as specified.

3. The combination with the stool-pedestal and the segmental rack-bar, of the lower straddle-arms 6, the upper straddle-arms 7, said arms 6 and 7 having independent pivotal connection with the stool-pedestal and held to straddle the rack-bar; the foot-rest pivotally connected to the outer ends of the arms 6 and 7, and a detent comprising a rack-bar journaled on the arm 6 and having a crank or loop portion adapted to engage the rack-bar; a spring for normally holding said loop portion in engagement with the rack-bar, and a crank-bar forming a part of such rack-bar, substantially as shown and for the purposes described.

JOHN W. SMITH.
